3 Sheets-Sheet 3

UNITED STATES PATENT OFFICE.

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH.

SUGAR-WASHING DEVICE.

Application filed June 19, 1920. Serial No. 390,131.

To all whom it may concern:

Be it known that I, EUGENE ROBERTS, a citizen of the United States, and resident of Salt Lake City, in the county of Salt Lake and State of Utah, have invented certain new and useful Improvements in Sugar-Washing Devices, of which the following is a specification.

This invention relates to apparatus for washing sugar or other material in a centrifugal basket after the juice or syrup has been centrifugally extracted therefrom and is in the nature of an improvement upon the washing apparatus shown in the Roberts and Gibson United States Letters Patent 1,224,095 dated April 24, 1917.

The present invention is intended to simplify the construction of the apparatus, improve its operation and obtain more precise or exact determination of the period of the washing or spraying operation. In general the invention comprises a constantly rotating shaft combined with an intermittently connected timing shaft and automatically controlled timing mechanism with suitably combined valve closing and nozzle actuating connections by which the duration of the period of washing is exactly controlled in accordance with a predetermined setting of a regulator.

Another feature of the invention comprises the combination of automatic timing mechanism and nozzle actuating and valve closing devices with a regulator operatively associated with a regulating dial member or index by which the exact setting can be readily determined appropriate to various grades of sugar to be treated.

These and other features of the invention will be explained in the following specification and will be defined in the claims hereto annexed.

In the accompanying drawings I have illustrated a preferred form embodying the principles of this invention in which:

Figure 1 is a front elevation showing the completely assembled device in operative position for use.

Figure 2 is an end elevation with a nozzle and partly broken away to show the valve chamber and valve.

Figure 3 is an end elevation with the end plate and supported parts removed to

show the intermediate construction and arrangement.

Figure 4 is a central section on a vertical plane extending from front to rear showing the working parts of the timing mechanism.

Figure 5 is a horizontal section showing the timing mechanism and working parts in plan view.

Figure 6 is a detail view of the crown gear which drives the timing mechanism showing the adjustable regulator in relation thereto as viewed on the plane $\alpha-\alpha$ in the direction of the arrow b in Fig. 4.

Figure 7 is a vertical face view on the plane $\alpha-\alpha$ showing the mutilated timing gear as viewed in the direction of the arrow a in Fig. 4.

Figure 8 is a front elevation partly in section with the end or dial plate broken away to show the intermediate working parts.

Figure 9 is a detail view showing the intermittently engaged transmission gearing for driving the timing shaft intermittently from the dial shaft.

In the practice of the invention as illustrated in the drawings I provide a suitable casing A having two circular open sides corresponding respectively to the front and side faces thereof each of which is closed by a removable head or plate as hereinafter described.

On the open side of the casing is removably secured a face plate 1 having integrally cast therewith a valve casing 2 provided with a partition 2^a forming a circular seat for the plunger valve 3 which when seated firmly to the valve opening or port prevents the flow of water through the valve chamber. At the opposite ends of the valve chamber or water passage are provided flanges 41 and 42 the latter adapted to form a flanged connection with the liquid supply pipe 60 while the former has a flanged connection with the flanged coupling 40 in which the oscillatory nozzle or spray pipe 4 is pivotally mounted so as to permit oscillation of the pipe 4 and the spray nozzle 5 carried at its end and through which the water is distributed in a

fan-like spray as described in the above-mentioned Roberts and Gibson patent.

The oscillation of the nozzle or spray member is effected by a split hub lever 6 whose separable semi-circular collar 7 is clamped around the horizontal portion of 5 the elbow shaped nozzle pipe 4 in any desired position of adjustment. At its free end, the arm 6 is provided with a stud or roller 6^a engaging a wave-like groove formed in the actuating cam 8 that is secured to the timing or worm shaft 9 which 10 also actuates the timing mechanism.

In the side wall of the casing opposite to that carrying the valve chamber is mounted a short power shaft 10 to which power is 15 provided by any suitable means as by a grooved pulley 11 driven by belt connection from any convenient shaft outside of the machine.

Pivottally mounted upon this power shaft 20 10 is a pinion supporting frame or double plate 13 whose branches straddle the driving pinion 12 that is secured to the inner end of the power shaft. Rotatably supported upon a stud or bearing pin 50 secured in this 25 pivotal frame 13 is a pinion 14 which is permanently intermeshed with the power pinion 12. Adjacent to the pinion 14 but normally out of engagement therewith is a pinion 15 secured to the worm shaft 9 by 30 which the worm shaft is driven when the mechanism is set in operation by the shifting of the pinion 14 into mesh with the pinion 15.

A fixed bearing stud or shaft 24 extends 35 through the casing from front to rear and is held against rotative movement by a clamping nut 24^a having threaded engagement with the reduced end of the shaft 24 which projects through the rear end of the 40 casing as shown in Figure 4. Around the front end of this shaft and projecting through the front or dial plate 23 is rotatably mounted the flanged sleeve 19 from whose flange projects rearwardly a stud or 45 lug 20 which stud or lug can be shifted circumferentially around the shaft by the partial rotation of the sleeve 19 which is effected by an external arm 21 secured to the end of said sleeve and having, as shown in 50 Figures 1 and 2, at its free end a headed plunger pin 22 which is normally spring-pressed into engagement with a series of locking holes formed in the face plate 23 concentrically around the axis of said sleeve 55 or regulating member. This perforated plate 23 therefore acts as an index or dial plate with the numbered holes to indicate the various setting positions of the regulator as will be hereinafter explained.

60 Rotatably mounted on the cylindrical sleeve 19 is the hub 17 of a worm gear 16 which continually meshes with the worm of the worm shaft 9 so that the gear 16 rotates as long as the worm shaft is in rotation.

The stem 30 of the valve 3 extends upwardly through the stuff box or gland 32 formed on top of the valve chamber, and through the medium of an adjustably connected member 31 has pivotal connection 70 with a short lever 27 secured to the transverse rock shaft 25 to which also is secured the hand lever 26 by which the valve is opened and the timing mechanism set in operation as will be explained. 75

The principal members of the timing mechanism comprise a non-rotatable sleeve 34 slidably mounted on the shaft 24 to which it is splined by a headed pin 47 projecting through a slot in the top of said sleeve, and the rotatable timing gear 35 which is rotatably mounted upon the front end of the sleeve 34 and is normally pressed in a contra-clockwise direction by the coil spring 38 one end of which is pinned to the 80 mutilated gear or timing member 35, the other end being pinned to the non-rotatable sleeve 34. From the front face of the mutilated gear 35 projects a stop pin 37 arranged to cooperate with the stop lug 20 of the regulator so that the stop lug 20 acts as a stop to limit the rotation of the member 35 in a contra-clockwise direction as viewed from the front under the tension of the coil spring 38. 90

It will be understood that the circumferential adjustment of the stop lug 20 by means of the regulator arm 21 will serve to change the position at which the stop pin 37, and consequently the timing member 35, 100 is held thereby varying the initial or circumferential position of the timing member 35. As will be hereinafter explained the timing member when set in action always acts at a predetermined point, hence the 105 setting at its initial position circumferentially will determine the period of duration of its rotation.

The timing member 35 is rotated whenever its crown teeth or projections 36 formed 110 on the front face thereof are brought into intermeshing engagement with any of the teeth of the crown gear 18 formed on the rear face of the worm gear 16 as shown in Figures 4, 6 and 7. This intermeshing is 115 effected by the longitudinal or sliding movement in a forward direction of the sleeve 34 carrying the timing member 35 against the crown gear teeth 18. Such forward movement is caused in the first instance by rocking the transverse shaft 25 in a clockwise direction by lifting the hand lever 26 such shifting movement being effected by means of an arm 33 formed on the rock shaft 25 whose rounded free end engages a transverse slot at the rear end of the sleeve or carriage 34. On the side of the sleeve 34 adjacent to the pinion 14 is formed a vertical slotted lug 49 into whose slot projects the stud or pin 50 which forms the support 120 125 130

ing axis for the pinion 14. Hence this forward movement of the sleeve acts through this pin connection to throw the transmission pinion 14 into mesh with the worm 5 shaft pinion 15 to cause the rotation of the worm shaft, the same movement resulting in operatively connecting or engaging the timing member 35 with the crown gear 18 by which the former is rotated.

10 A coiled spring 39 secured to the shipper arm 33 and to a fixed part of the machine acts to cause a rearward movement of the sleeve 34 by which the timing member 35 is shifted out of operative position. To prevent this automatic rearward shifting of the sleeve or carriage 34, until the predetermined time when it is desired to disengage the timing member from the crown gear, I employ a dog 45 which is pivotally mounted on the rear end of the sleeve and whose under side is formed with a hook or shoulder 46 adapted to drop over and engage the front side of the splined pin 47 when the sleeve is shifted forward in position to operate the timing mechanism.

On the periphery of the rotatable timing member 35 is provided a projection in the form of a set screw cam pin 48 which acts when it reaches the uppermost or vertical position in line with the forward end of the dog 45 to lift the said dog out of interlocking engagement with the pin 49 thereby allowing the torsion spring 39 to withdraw the sleeve and timing member from operative position through the turning of the rock-shaft.

For greater security the dog is engaged upon the opposite side by the vertical lugs 44 and 49 (Fig. 5) to relieve the pivoted pin 40 of the dog of sidewise thrust when the projecting cam pin 48 rides against the front end of the dog in the act of lifting it to releasing position.

Since the forward end of the rock-shaft 45 has operative connection with the valve 3 through the valve stem and the short arm 27, it will be seen that the raising of the hand lever 26 acts to open the valve as well as set the timing mechanism in operation, 50 while the automatic release or disengagement of the timing mechanism being caused by the reverse movement of the rock shaft under the influence of the torsion spring 39 will coincide with the closing of said valve 55 by the rock shaft.

Since the dog or latch 45 has a constant or uniform position circumferentially of the axis of rotation of the timing member 35 it will be seen that the timing mechanism 60 always ceases to act at a predetermined point. Since the spiral spring 38 normally presses the timing member 35 around in a contra-clockwise direction until it is arrested by the engagement of its stop pin 37 65 with the stop lug 20 of the regulator, it will

be seen that the circumferential shifting of the regulator will correspondingly shift the initial position of the timing member so that, obviously, the farther the timing member is set in a clockwise direction the shorter 70 will be the arc through which the timing member 35 will have to travel before reaching its angle of position and, hence, the shorter will be the duration of the washing period which is terminated by the closing of 75 the valve, which, is effected by the torsion spring 39 and connections as soon as the dog 45 is lifted and ceases to act as a detent.

What I claim is:

1. In a machine for washing sugar in centrifugals and the like, the combination of a pulley driven shaft, a cut-off valve, a rotatable timer for determining the period that the valve remains open, intermediate connections between said shaft and said timer comprising a worm gear and a worm in constant mesh with each other and disconnectible on one side from the pulley driven shaft and on the other from the timer when the latter acts to cause the closing of 80 the valve, and a timer regulator adjustable to vary the arc of rotation permitted said timer, substantially as described.

2. In a machine for washing sugar or the like, the combination with a spray nozzle and its cut off valve, of spring actuated valve-closing mechanism, a detent for preventing the closing of the valve, a rotatable timing member arranged to release the detent after rotating through a predetermined 95 arc of rotation, a worm actuated driving gear arranged coaxially with the rotatable timing member to have operative connection therewith until the connection is automatically broken by the release of said detent, substantially as described.

3. In a machine for washing sugar or the like, the combination with an oscillatory spray nozzle and its cut-off valve, of automatic valve-closing means, a releasable detent for preventing the valve closing means from acting, a rotatable timer acting to release the detent after rotation through a predetermined arc, an actuating gear arranged coaxially with the timer to have releasable driving connection therewith, a regulating stop member adjustable about the axis of the timer to vary the arc of its rotation before releasing the detent, and a starting lever acting to open the cut-off 110 valve and operatively connect the timer with its actuating gear, substantially as described.

4. In a machine for washing sugar the combination of a rotary actuating shaft, a cut-off valve closing means therefor, a sliding carriage, a timing member rotatably mounted on said carriage and shiftable thereby into operative position to be driven from said actuating shaft, a detent acting to hold said carriage against reverse move- 125 130

ment during the washing operation said detent being released by said timing member at a predetermined point in the rotation of the timing member, the valve closing mechanism being held against action by said carriage until said detent is released, substantially as described.

5. In a machine for washing sugar, the combination of a rotary actuating shaft, re-
10 leasably connected driving means therefor, an actuating gear driven by said shaft, a rotatable timing member movable in the direction of its axis, to be operatively engaged with said gear by the opening movement of
15 the valve mechanism, a valve, and valve controlling mechanism operatively associated with said timing member to act to close the valve when the timing member has rotated through a predetermined arc, substantially
20 as described.

6. In a machine for washing sugar, the combination of a rotary actuating shaft, a gear driven thereby, a cut-off valve, a movable carriage, a rotatable timing member
25 mounted on said carriage to be moved into operative engagement with said gear by the opening of the valve, valve closing mechanism held against action by said carriage when the timing member is engaged with
30 said gear, said carriage being released to permit the action of the valve closing mechanism when the timing member has rotated through a predetermined arc, substantially as described.

35 7. In a machine for washing sugar, the combination of a continuously rotating driving member, an actuating shaft, means for forming a disconnectible driving connection between said driving member and said shaft, a cut-off valve, valve closing mechanism, a
40 movable carriage operatively connected with said valve closing mechanism to prevent it from normal action, a timing member mounted on said carriage and having dis-
45 connectible driving connection with said actuating shaft said carriage acting simultaneously to establish operative connection between said driving member and said timing member with said shaft and to cause their
50 simultaneous release from driving connection therewith, substantially as described.

8. In a machine for washing sugar, the combination of an actuating shaft, intermittently connected driving means therefor, a
55 timing member arranged to be temporarily shifted into driven connection with said actuating shaft, a carriage acting to operatively connect said driving means and said timing member with said actuating shaft, a
60 cut-off valve, valve closing mechanism inter- connected with said carriage to be held against action while the aforesaid driving connections are maintained and to release

said valve closing mechanism when the aforesaid driving connections are disconnect-
65 ed, substantially as described.

9. In a machine for washing sugar, the combination of a rotatable actuating shaft, an actuating gear driven thereby, a slideable carriage movable toward and away from, said gear, a rotatable timing member mounted on said carriage to be shifted into operative engagement with said gear, a detent arranged to automatically lock the carriage with the timing member in engagement with
75 said gear, said timing member acting to release said detent at a predetermined point in its rotation, a shut off valve, valve closing mechanism interconnected with said carriage to be held inactive when the timing member
80 is engaged with its actuating gear and to be released to close the valve when the timing member has reached a predetermined point, substantially as described.

10. In a machine for washing sugar, the combination of a casing having a transverse shaft, a gear rotatably mounted on said shaft, a regulating member rotatably mounted on said shaft inside said gear, a carriage mounted to slide longitudinally of said shaft toward and away from said gear, a detent mounted on said carriage, a timing member rotatably mounted on said carriage and movable by said carriage into operative connection with said gear and provided with means for releasing said detent at a predetermined point in its rotation, a rock-shaft having an arm interconnected with said carriage, a valve, and a valve stem having connection with said rock-shaft, and a spring normally tending to close said valve and withdraw said carriage to disconnect said timing member from said gear, substantially as described.

11. In a machine for washing sugar, the combination of an actuating worm shaft and worm gear connected therewith, lateral gear teeth, a timing member arranged to be shifted into and out of operative engagement with said gear teeth to be rotated thereby, an adjustable stop member, a spring normally holding said rotatable timing member against said stop member when the timing member is disengaged from the gear, and means for simultaneously starting the rotation of said worm shaft and said timing member, a cut-off valve, valve closing mechanism, and means controlled by the timing member for releasing said valve closing means and disengaging the timing member from operative connection with said gear, substantially as described.

In witness whereof, I have subscribed the above specification.

EUGENE ROBERTS.
